UNITED STATES PATENT OFFICE.

LUCIA H. MANNESCHMIDT, OF NEW BRUNSWICK, NEW JERSEY.

BOILER-STAND.

1,236,329.

Specification of Letters Patent.

Patented Aug. 7, 1917.

Application filed December 13, 1915. Serial No. 66,643.

To all whom it may concern:

Be it known that LUCIA H. MANNESCHMIDT, a citizen of the United States, residing at New Brunswick, New Jersey, in the county of Middlesex and State of New Jersey, have invented new and useful Improvements in Boiler-Stands, of which the following is a specification.

This invention relates to water distribution, and more especially to detachable pipe couplings; and the primary object of the same is to produce a coupling formed from a single piece of metal or casting having a plurality of arms or branches so disposed that the product is especially useful in connecting a stand boiler with its source of water supply whatever the latter may be, and providing also a valved drain branch for cleaning out the boiler and pipes and a socketed branch for supporting the casting and boiler from a suitable base.

I further aim to produce a structure of this type having a removable shell which serves as the seat for the drain valve, and provided with a port so disposed that the shell is located at the juncture of the bores of several branches of the casting, whereby a suitable tool may be introduced into any of them when the shell is to be withdrawn.

I further aim to provide a boiler stand including a water supply connection having branch portions respectively disposed in the same horizontal line with each other, and a drain passage disposed intermediate said portions and with such regard thereto as will permit of a complete cleaning out of all portions of the connection wherein sediment or incrustation may accumulate and one wherein a cleaning wire or tool may be readily inserted into the bore of any open branch.

A still further object of the invention resides in the provision of a stand, including a connection having a portion designed to be attached to the supply source and a valved draining branch having a removable valve seat disposed relatively of the axial bore of the structure whereby to permit the seat to be exposed in a manner which will permit the same to be substantially and expeditiously manipulated by a suitable extracting or removable tool.

In the drawings forming a part of this specification and in which like reference

numerals indicate similar parts throughout the several views:

Figure 1 is a vertical section through a portion of a boiler showing the application of a stand thereof.

Fig. 2 is a vertical section through the connecting member.

Fig. 3 is a section taken on the line 3—3 of Fig. 2.

The device is designed for wholly supporting the boiler from the base or bottom thereof and it consists of a relatively broad base flange 1, having a vertical central boss 2 in which is fitted the lower end of a pipe section or standard 3, the latter being adapted to be arranged in a line with the vertical axis of the boiler as shown in Fig. 1. The upper end of the pipe section or standard 3 is fitted in a socket 4 formed in the lower or depending branch or arm 5 of a connecting member 6.

The latter is preferably a casting substantially of cruciform configuration as shown in Fig. 3 and in line with the branch 5 it is provided with an upper branch 7 threaded as at 8 for connection with the central boss 9 upon the crown or bottom wall 10 of the boiler. This branch has adjustably mounted thereon a clamping flange or nut 11 which is adapted to be adjusted against the mentioned wall 10 of the boiler as shown in Fig. 1. As stated, the casting 6 is substantially of cruciform configuration, being provided with horizontally aligned side branches 12 and 13 having a common bore 14 which extends entirely through the casting and intercepts the bore of the upper branch 7. The branch 12 may be connected with the water back of a range, while the branch 13 is designed to be connected with the coil of a gas or electric heater. The branches 12 and 13 are identical in construction so that either may be connected with the mentioned water circulating sources.

Any branch may be closed by a suitable plug, not shown, when it is desired to connect the boiler with only one source of water supply or circulating system. The branches 12 and 13 are provided with coupling nuts 15 which may be connected in the usual manner with the water supply sources.

The casting 6 is provided further with a horizontal boss or front branch 16 having an internal valve chamber 17 whose outer

end is closed by a suitable cap 18 in which is designed to work a controlling valve stem 19. This stem is movable axially of the bore of the chamber and it is provided with a thread 20 which co-acts with a similar thread 21 formed in a removable sleeve 22 mounted within the valve chamber. In advance of the sleeve, the stem is provided with a valve head 23 appreciably larger than the bore of a removable valve seat 24. This seat is in the form of a thin metallic shell of a size adapted to fit closely within and accommodate itself to a reduced passage or port 25 formed in the casting and connecting the chamber 17 with the bore 14 at a point in the latter between the inner ends of the branches 12 and 13 and in a line with the branch 7. The inner end of the shell is crimped or flanged, as at 26, against the inner walls of the casting around this port; and as shown in Fig. 2, the outer end of the shell is curved or rounded gently in order that it will accommodate itself to a similarly curved rib 27 formed upon the inner wall of the valve chamber, into contact with which rib this end of the shell is pressed by said head at the first closing of the valve.

Incident to the described relation of the shell to the branches 12 and 13, it is evident that the crimped flange 26 may be exposed from every end of the connection when it is desired to extract or remove the seat. A suitable tool may be manipulated around all sides of the seat in order to release the flange 26 from the inner walls of the connection.

The passage which is formed through the removable seat opens directly to the valve chamber 17 and the latter, in turn, opens into a drain branch or extension 28 which preferably extends forward and downward at an angle to the vertical axis of the connection. The valve head 23 is thus adapted to move across the upper end of the drain branch and the latter will be securely sealed from the boiler when said valve head 23 is operatively engaged against its seat. The sleeve 22 terminates considerably forward of the branch 28 and it is desired to co-act with the valve proper 23 to form a stop therefor.

From the construction herein set forth, it obviously follows that the boiler may be quickly blown-off or drained at the convenience of the operator. The peculiar relative disposition of the several branches of the connecting member or casting affords means whereby a wire or other suitable tool may be trained through all of the several branches or extensions of the structure and the inner walls thereof relieved of all objectionable sediment or incrustation. The alinement of the branches 7, 12 and 13 and their specific relation to the valve seat

should not be lost track of as they are thought to be essential toward permitting the objects preceding herein to be fully carried into practice. I wish also to call attention to the diameter of the valve shell 70 relatively of the bore 14, the latter being greater than the former whereby to permit an extracting tool to freely find its way around the marginal inner flange of the shell during the process of removing the 75 latter.

What is claimed as new is:

1. A pipe coupling of the class described comprising a casting having an upright branch and two side branches, the bores of all the three branches intersecting at a common point, a valved drain branch, and a port between its bore and said point, and a depending branch having a socket out of communication with said bores; combined with a supporting standard whose upper end is seated in said socket.
2. A pipe coupling of the class described comprising a casting having an upright branch and two side branches, the bores of all branches intersecting at a common point, a front branch constituting a valve chamber and whose bore is connected by a reduced port with said common point, an oblique branch whose bore communicates with said chamber, and a depending supporting arm; combined with a support connected with said arm, a valve within said chamber, means for operating it manually, and a valve seat removably mounted in said port and accessible from any of the several branches.

3. In a pipe coupling, the combination with a casting having a plurality of branches standing in one plane and whose bores intersect at a common point, and another branch at right angles to said plane, constituting a valve chamber, and having a drain opening, the casting having a port connecting the bore of the last-named branch with said common point; of a manually operable valve in the last-named branch, and a valve seat removably mounted in said port and accessible from any of the several branches.

4. In a device of the class described, the combination with a casting having a plurality of branches whose bores intersect at a common point and an additional branch constituting a valve casing and having a drain outlet, said casting having a port connecting the valve chamber with said common point and of smaller size than the bore of any branch, and a manually operable valve within the chamber having a head larger than said port; of a shell closely fitting said port with one end constituting the valve seat and the other end flanged against the wall of the casting at said point of intersection and accessible through the bores of the various branches.

5. In a device of the class described, the

combination with a casting having a plurality of branches whose bores intersect at a common point and an additional branch constituting a valve casing and having a drain outlet, said casting having a port connecting the valve chamber with said common point and of smaller size than the bore of any branch, and a manually operable valve within the chamber having a head larger than said port, the casting having a rib in the valve chamber opposite the head and around said port; of a shell closely fitting said port and having one end overlying said rib to constitute the valve seat and the other end flanged against the wall 15 of the casting at said point of intersection and accessible through the bores of the various branches.

In testimony whereof I, affix my signature in presence of two witnesses.

LUCIA H. MANNESCHMIDT.
